DESIGN FOR A THEATER

John S. Clarke, Jr., New York, N. Y., assignor to
Pix Theatres Inc., New York, N. Y., a corpora-
tion of New York

Application June 17, 1933. Serial No. 48,430

Term of patent 14 years

To all whom it may concern:

Be it known that I, JOHN S. CLARKE, Jr., a citizen of the United States, residing at New York, in the county of New York and State of New York, have invented a new, original, and ornamental Design for Theater, of which the following is a specification, reference being had to the accompanying drawing, forming a part thereof, in which:

Fig. 1 is a perspective view of a theater embodying my new design.

Fig. 2 is a front elevation of the theater.
Fig. 3 is a top plan view of the theater.
Fig. 4 is a side elevation taken from the right-hand side of Fig. 2.
Fig. 5 is a rear elevation.
Figs. 3, 4 and 5 are on reduced scale.

I claim:
The ornamental design for a theater, substan-
tially as shown.

JOHN S. CLARKE, JR.
